AMPLIFIER

Donald E. Norgaard, Cohoes, N. Y., assignor to
 General Electric Company, a corporation of
 New York

Application May 18, 1940, Serial No. 335,947

5 Claims. (Cl. 178—7.1)

This invention relates to amplifiers and has for an object to provide a wide-band coupling amplifier which transmits a voltage between two points and prevents the introduction into the transmitted voltage of extraneous voltages which may fortuitously exist between the two points.

It is a more particular object of my invention to provide wide-band amplifying apparatus which is necessarily connected at spaced points of a chassis or the like and in which fortuitous interfering currents which flow through the chassis are prevented from affecting the voltage which is amplified through the apparatus.

The features of my invention which I believe to be novel are set forth with particularity in the appended claims. My invention itself, however, both as to its organization and method of operation, together with further objects and advantages thereof may best be understood by reference to the following drawing in which Fig. 1 illustrates apparatus embodying one form of my invention; Fig. 2 illustrates an elaboration and modification of the embodiment of Fig. 1; Fig. 3 represents a further modification of Fig. 1; and Fig. 4 illustrates a different embodiment of my invention.

Referring to Fig. 1, there is illustrated a source 10 of alternating voltage which is transmitted through a pair of conductors 11 and 12 to an electron discharge amplifying device 13, which transmits amplified waves to a load device 14. One terminal of the source 10 is connected to a suitable ground connection 15 which serves also to carry space current passing from the cathode 16 of the device 13 through the conductor 12, to a second suitable ground connection 17 and to the negative terminal of a source 18 of direct potential. The positive terminal of the source 18 is connected through the load 14 to the anode 19 of the device 13, thus completing a circuit for the space current therethrough.

Waves from the source 10 which are transmitted through the conductors 11 and 12 appear across a resistor 20 with which the transmission line formed by these conductors is terminated. The voltage on resistor 20 is coupled to the first or control electrode 21 and cathode 16 of the device 13 by a coupling condenser 22. The control electrode 21 is conductively connected through a resistor 23 and a source 24 of biasing potential to the cathode 16. The screen electrode 25 of device 13 is connected through a source 26 of potential to the cathode 16. The source 26 is suitably by-passed for high frequency current with a by-passing condenser 27, and serves to

5 maintain the second electrode 25 at a substantially constant positive potential with respect to the cathode 16, which potential is preferably not more positive than the minimum positive potential of the anode 19. A third control electrode or suppressor grid 28 is connected directly to the cathode 16.

An electron discharge device provided with electrodes such as are shown, and with means 10 for maintaining bias potentials on the control electrodes which are uninfluenced by any alternating voltages, has an exceedingly high anode to cathode impedance. Such a device allows a substantially constant current to pass from its 15 anode to its cathode, even when the potential therebetween is varied over wide ranges. The device is at the same time preferably so constructed as to be exceedingly sensitive to potential changes of the control electrode 21, which can be made to 20 produce very large changes in the anode to cathode current.

By the circuit shown it has been provided that 25 noise voltages which may fortuitously exist between the ground points 15 and 17 cannot substantially affect the electron current which flows through the load device 14. This is true because the circuit is so arranged that voltages existing 30 between the points 15 and 17 can produce voltage changes only between the cathode and anode of the device 13 and cannot affect the potential on any control electrode thereof, and because the current flowing between the anode and cathode is substantially independent of the voltage 35 therebetween.

The invention is at present of greatest use in 40 the exceedingly wide band amplifiers required in television apparatus, which are, by their nature, very sensitive to noise voltages. One such circuit in which the invention has been used with great 45 success provides for the transmission of video voltages from a portable television camera by wire to an amplifier in a remote fixed location.

Such a system is schematically represented in 45 Fig. 2, wherein certain parts which correspond 50 with like parts shown in Fig. 1 are given like reference characters. In this figure the source 10 may, for example, represent a camera tube for translating light into a video signal. An electron discharge device 29 serves to amplify the video signal from the source 10 before transmission from the portable camera apparatus through the conductors 11 and 12 to an amplifier in a remote fixed position, which amplifier includes the device 13. The amplifier 29 serves to couple 55 the video signal from the source 10 to the trans-

mission line formed by the conductors 11 and 12. The cathode 30 of the device 29 is connected through conductor 11, resistor 20, and conductor 12 to a central point of a source 32 of unidirectional potential, whose positive terminal is connected to anode 34 of the device 29. The negative terminal of the source 32 is connected through the source 10 of video signals to a first or control electrode 35 of the device 29. A screen electrode 36 is supplied with positive potential through a resistor 37 from the positive terminal of the source 32, and is by-passed for high frequencies to an input terminal of transmission line 12 with a by-passing condenser 38. A gas discharge voltage regulating device 31 is connected across condenser 38 to aid in maintaining the screen potential more nearly constant.

Bias potentials for the control electrode 21 and the screen electrode 25 of the device 13 in this embodiment of my invention may be provided for in a somewhat different manner than by providing separate sources of potential 24 and 26 as in Fig. 1. The control electrode 21 of the device 13 is supplied through a resistor 39, a second resistor 40, and a wire 41, which, parallel with the conductors 11 and 12, leads to the portable camera apparatus and is connected to the negative terminal of the source 32. A point between the resistors 39 and 40 is by-passed to the cathode 16 through a by-passing condenser 42. A biasing voltage is therefore supplied across the condenser 42 for the control electrode 21, which potential is not influenced by any voltage appearing between the ground points 15 and 17.

The anode 19 is connected in series through a resistor 43, an inductance 44, a resistor 45, and a source 46 of direct potential to ground point 17, the ground point 17 being connected to the source 46 at an intermediate point, and the positive terminal thereof being connected to the resistor 45. The junction between the screen electrode 25 and the by-passing condenser 27 is connected through a resistor 47 to the positive terminal of the source 46. The by-passing condenser 27 should be made sufficiently large so that voltage which appears between the ground connections 15 and 17, and consequently between the cathode 16 of the device 13 and the ground connection 17, may be effectively absorbed by the resistor 47 and thereby prevented from substantially affecting the potential of the screen electrode 25. The amplifier including the device 13 therefore functions in substantially the same way as in the apparatus illustrated by Fig. 1, since voltages between ground connections 15 and 17 can appear only between the anode and cathode of device 13.

A point between the inductance 44 and the resistance 45 is connected through a by-passing condenser 48 to the ground connections 17. This condenser 48 is provided to smooth the direct potential from the source 46, which usually is a source of rectified alternating current. In addition to providing such smoothing, the condenser 48 constitutes an element of an improved wide-band coupling circuit disclosed in my copending application for Letters Patent, S. N. 328,045, filed April 5, 1940, for Amplifier coupling circuit, and assigned to the same assignee as the present application. It should be noted particularly that the condenser 48 is not connected between the cathode 16 and the resistor 45, but is rather connected to the ground point 17 so that the entire anode circuit of the device 13 is associated with the ground point 17 (Fig. 2) exactly

as in the case of the load device 14 and the source 18 shown in Fig. 1. If the condenser 48 be connected from the cathode 16 to the resistance 45, noise voltage between the ground connections 15 and 17 would appear across the series circuit comprising the source 46, resistance 45, the condenser 48, and the wire 12. Since a noise potential would then be developed across the resistor 45 corresponding to the noise voltage between points 15 and 17, it would appear between the anode 19 of the device 13 and the ground point 17 and would thereby be introduced into the succeeding circuits of the signal amplifying channel. That is, the voltage across the resistance 45 would be repeated through the following stages of amplification whose input terminals would include resistance 45 therebetween. In accordance with my invention this is avoided by connecting the condenser 48 to the ground connections 17.

For purposes of illustration, a wide-band amplifier coupling is shown for transmitting voltage variations from the anode 19 of the device 13 to a further electronic amplifier device 49 which is associated with the ground point 17. This wide-band amplifier circuit is described and claimed in my copending application mentioned above. The anode 19 is coupled through a coupling condenser 50 to a first or control electrode 51 of the device 49. The condenser 50 is of small value so that its impedance, while low at the high frequency end of the transmission band, is rather high at the low frequency end. The condenser 50 is shunted by a resistor 52, a large condenser 53, and a resistor 54 in series. The control electrode 51 is connected through a resistor 55 to the negative terminal of the source 46, so that it is maintained thereby at a suitable bias potential. By properly proportioning the size of the components 43, 44, 45, 48, 50, 52, 53, 54 and 55, the transmission characteristic of this coupling network may be made substantially flat over a wide-band. The anode 56 of the device 49 is connected through a resistor 57, which represents any suitable load device, to the positive terminal of the source 46.

A television amplifier such as that illustrated in Fig. 2 may be modified slightly so as to be capable of transmitting and amplifying direct currents as well as a wide frequency band of alternating currents. An amplifier capable of transmitting direct current components is illustrated in Fig. 3 in which certain parts, which correspond to parts illustrated in Fig. 2, are given like reference characters.

In Fig. 3 the amplifier including the device 29 is identical with that in the apparatus illustrated in Fig. 2. A source 58 is illustrated in place of the source 10 and is one which produces a direct current component together with a wide frequency band of alternating currents.

The conductor 11 is connected to the control electrode 21 through a source 58 of bias potential which is by-passed for high frequencies by a by-passing condenser 59. The capacity to ground point 17 of the source 58 and the condenser 59 must be of minimum value, for otherwise noise voltage existing between the ground connections 15 and 17 would be introduced at the control electrode 21. This is easily accomplished, since the condenser 59 need be only a very small condenser and the source 58 may be a very small dry cell. The cathode 16 is connected to the wire 12 through a small resistor 60 to introduce some degeneration into the am-

plifier including the device 13 for improvement of the linearity thereof and for production of bias voltage, which, in some designs, may be made sufficient to allow the source 58 and its by-pass condenser 59 to be omitted. When the device 13 is used to amplify direct potentials it is advisable to provide a screen potential stabilizer of good regulation, such as a gaseous discharge tube 61 connected in shunt across the condenser 27. This tube 61 is of the voltage-regulator type which maintains a constant voltage between its terminals, even during large changes of current therethrough.

The coupling means between the devices 13 and 49 is modified for the transmission of direct potential by shunting the coupling condenser 50 with a resistance 62, the grid terminal of which is connected through resistance 55 to the negative terminal of source 46. The value of resistance 62 is equal to the sum of the resistors 52 and 54 of Fig. 2. When the components of this wide-band amplifier are correctly proportioned for equal transmission over the frequency band, the resistor 62 is of a rather large value, so that by increasing the negative bias voltage supplied from the source 46 through the resistor 55 to the control electrode 51 a proper bias voltage on the grid of device 49 is maintained. The increase in negative biasing potential required from the source 46 is usually small.

Even though two stages of an amplifier are placed closely adjacent to each other on a common chassis, difficulties have been encountered due to random currents fortuitously existing within the chassis. Provision has been made to prevent the introduction of voltages arising therefrom into an amplifier by using the same principle which underlies the embodiments of Figs. 1, 2 and 3. Referring to Fig. 4 there is shown a source 70 of video signal voltage which is amplified through an electron discharge device 71 and a second similar device 72 and transmitted to a load device 73. A cathode 74 of the device 71 is connected to one point 75 on a chassis 76 through which noise currents may flow. Cathode 77 of the device 72 is connected to a different point 78 on the chassis 76.

One terminal of the source 70 is connected to the cathode 74 and the other terminal is coupled through a suitable coupling means such as condenser 79 to the first or control electrode 80 of the device 71. Bias voltage is maintained on the control electrode 80 by its connection through a resistor 81 and a source 97 of bias potential to the cathode 74.

The positive terminal of a source 82, of which an intermediate point is connected to the point 78, is connected through resistors 83 and 84 and an inductance 85, all in series, to the anode 86 of the device 71. The screen electrode 87 of the device 71 is maintained at a fixed positive potential with respect to the cathode 74 by connection through a resistor 88 to the positive terminal of the source 82 and by a by-passing condenser 89 connected from electrode 87 to the cathode 74. A point between the resistors 83 and 84 is connected through a by-passing condenser 90 to the cathode 77 of device 72.

Any fortuitous noise voltage which may exist in the chassis 76 produces currents which flow in the circuit through the condenser 90, resistor 88, inductance 85, the anode 86, and cathode 74 back to the point 75 of chassis 76. Since the impedance of the device 71 is far higher than any other impedance in this circuit, practically the

entire noise voltage appears between the anode and cathode of the device 71, the current in the anode circuit of which device is substantially constant during changes in anode voltage over a predetermined range, so that signal voltage across the inductance 85 and the resistance 84 is substantially unaffected by voltage between points 75 and 78 on the chassis.

The anode 86 of the device 71 is coupled through a coupling condenser 91 to a first or control electrode 92 of the device 72. The condenser 91, which is provided to transmit high frequencies, is shunted by a series circuit comprising resistor 93, a large condenser 94, and a resistor 95, which combination acts to transmit low frequencies. The control electrode 92 is connected through a resistor 96 to the negative terminal of the source 82, which maintains the bias voltage of control electrode 92 at a proper value. By proportioning the constants of this coupling circuit in a manner similar to that shown in Fig. 2, the amplifier can be made to have uniform response over a wide-band of frequencies.

The condenser 90, which connects the anode circuit of the device 71 to the cathode circuit of the succeeding device 72, forms a circuit for noise voltage passing through device 71. The device 71, which has the characteristic that the anode current flowing therethrough remains substantially unaffected by any change in voltage in the anode circuit, prevents introduction of the noise voltage into the signal transmitted through the devices 71 and 72. The bias voltage for the respective control electrodes must be supplied from a source so connected that noise voltage cannot appear on the control electrode. However, it is clearly seen that provision for bias voltages for these electrodes is not difficult with the circuit arrangements shown.

It will be apparent to those skilled in the art that the circuits I have shown and described may be rearranged in many ways, while still confining the noise voltages to a path including the space between the anode and cathode of a suitable electron discharge device, the impedance of which is so high that the current through it is not affected by such voltages. Although I have illustrated such discharge devices as multigrid tubes, it is quite feasible to utilize triodes of high anode impedance in carrying out my invention.

While I have shown a particular embodiment of my invention, it will, of course, be understood that I do not wish to be limited thereto, since different modifications may be made both in the circuit arrangement and instrumentalities employed, and I aim by the appended claims to cover any such modifications as fall within the true spirit and scope of my invention.

What I claim as new and desire to secure by Letters Patent of the United States is:

1. In combination, an electron discharge device having an anode, a cathode, and a control electrode, a circuit therefor requiring spaced ground points between which undesired voltage may exist, means for connecting said control electrode to ground only at one of said points, said means including a signal source, means connecting said cathode to ground only at said one point, means connecting said anode to ground only at another of said points, said cathode connecting means having substantial impedance at the frequency of signals from said source whereby said undesired voltage may appear between said cathode and said one ground point, the im-

pedance between said anode and cathode having a high value such that the current therein and the voltage on said control electrode is substantially unaffected by said undesired voltage, by reason of the fact that said undesired voltage between said ground points can appear only between said anode and cathode, and an output device responsive to said current.

2. In combination, an electron discharge device having an anode, a cathode, and a control electrode, a signal source at a remote point, conductors connecting said signal source between said control electrode and said cathode, said source and said device requiring spaced ground points between which undesired voltage may exist, means connecting said cathode and the conductor connected thereto to ground only at the ground point at said source, means connecting said anode to ground only at another of said ground points, said control electrode being connected to ground only at the ground point at said source, the impedance of said conductors being substantial at the frequency of signals from said source whereby said undesired voltage may appear on said control electrode, said anode and cathode having impedance therebetween of high value such that the current therethrough is substantially unaffected by changing voltage therebetween, whereby said undesired voltage does not affect said current or the voltage on said control electrode, and an output device responsive to said current.

3. In combination, a television camera and a remotely situated amplifier for video signals produced thereby, said camera and said amplifier requiring spaced ground points between which undesired voltage may exist, and said amplifier comprising an electron discharge device having an anode, a cathode, and a control electrode, a pair of conductors connected from said camera to said cathode and control electrode to impress video signals therebetween, means connecting said cathode and its conductor to ground only through the ground point at said camera, means connecting said anode to ground only through another of said ground points, said control electrode being connected to ground only at the ground point at said camera, the impedance of said conductors being substantial at the frequency of said video signals whereby said undesired voltage may be impressed on said control electrode, said anode and cathode having impedance therebetween of high value such that

the current therethrough and the voltage on said control electrode is substantially unaffected by said undesired voltage, and an output device responsive to said current.

5. In combination, an electron discharge device having an anode, a cathode, and a control electrode, a signal source, said source and said device having separated ground connections which may have undesired voltage therebetween, 10 circuits connected with said device including conductors connecting said source between said cathode and said control electrode and a circuit passing through said separated ground connections, said cathode being connected to ground only 15 through the ground connection at said source, said conductors having substantial impedance whereby undesired current variations produced in said conductors by said undesired voltage produce undesired voltage on said control electrode, and 20 means connecting every circuit connected with said device and passing through said separated ground connections through the anode and cathode of said device, said device having a characteristic such that current flowing in its anode 25 and cathode is substantially unaffected by said undesired voltage impressed therebetween, whereby said undesired voltage does not appear on said control electrode.

5. In combination, an electron discharge device 30 having an anode, a cathode, and a control electrode, a transmission line extending from a source of voltage to be amplified to said discharge device, one conductor of said line being connected to said cathode and the other conductor being connected to said control electrode, a connection for alternating currents from said cathode to a ground point only through the length of said one conductor so arranged that alternating current flowing in said one conductor must 35 flow through the anode and cathode of said device, said control electrode being connected to ground only at said ground point through said source, an output circuit connected between said anode and a second ground point and providing 40 the only ground connection for said anode, whereby undesired voltage existing between said ground points may affect the value of said alternating current undesirably, the impedance between said anode and cathode being of high value 45 such that the value of said current is not undesirably affected by said undesired voltage.

DONALD E. NORGAARD.
